WASHING MACHINE

Anthony W. Molinare, Oak Park, Ill., assignor to
 Electric Household Utilities Corporation, Chi-
 cago, Ill., a corporation of Illinois

Application October 11, 1937, Serial No. 168,383

6 Claims. (Cl. 68—133)

This invention relates to washing machines, such as used in the household, and more particularly, to machines of the type wherein the impeller member is mounted substantially centrally in the tub, and in spaced-apart relation to the walls and bottom thereof to permit free circulation of the washing fluid and clothes, around and beneath the impeller member. More especially, the present invention is directed to an improved washing machine construction, of the type wherein the impeller member is vertically reciprocated and simultaneously oscillated horizontally within the tub.

I am aware of several prior art constructions of washing machines, wherein the impeller member is reciprocated vertically and simultaneously oscillated in horizontal direction within the tub. To my knowledge, however, such prior art constructions have not proved commercially successful primarily due to the fact that the construction and arrangement of the impeller member is such as to preclude free circulation of the washing fluid and clothes, around and beneath the impeller member, while the same is reciprocated and oscillated. Another difficulty with such prior art constructions resides in the particular form or construction of the impeller member, which, in practically all instances, do not provide adequate action or motion of the washing fluid and clothes immersed therein, for expeditiously performing an efficient cleansing operation upon the clothes.

One of the primary objects of this invention is to provide, in a washing machine of the character described, a novel form of impeller member capable of producing an improved action of the washing fluid and clothes immersed therein, for performing an expeditious and efficient cleansing operation upon the clothes.

Another object is to provide a novel form of impeller member for use in a washing machine of the character above indicated, by virtue of which the washing fluid and clothes immersed therein are imparted vigorous motion for causing frequent turning and flexing of the clothes.

It is also an object of the present invention to provide an improved form of impeller member for use in a washing machine of the character indicated, by virtue of which the washing fluid and clothes immersed therein during one direction of simultaneous reciprocating and oscillating motion of the impeller member, are imparted a greater amount of circulatory movement than in the other direction of said combined reciproca-

tory and oscillatory motion of the impeller member.

Other objects and advantages of this invention will be apparent from the following description, taken in connection with the accompanying drawings, in which:

Fig. 1 is a view, part in elevation, part in section, of a washing machine embodying the present invention.

Fig. 2 is a top plan view of the impeller member.

Fig. 3 is a transverse sectional view through the impeller member, taken as indicated on line 3—3 on Fig. 1.

Fig. 4 is a side elevational view of the impeller member.

Fig. 5 is a vertical sectional view of the impeller member, taken as indicated at line 5—5 on Fig. 2.

Fig. 6 is a bottom plan view of the impeller member.

Fig. 7 is an enlarged fragmentary sectional view of the upper portion of the impeller member, showing the mode of attachment to the impeller shaft.

In the illustrated embodiment of my invention, the washing machine comprises an upwardly open tub 10, herein shown as of circular form, provided with a depending skirt 11 to which is rigidly secured a plurality of depending legs 12 for supporting the tub in proper spaced apart relation to the floor. The lower ends of the legs are rigidly connected and braced by a frame 14, which serves as a reinforcing structure, and in addition provides support for suitable drive mechanism for the impeller member, herein designated generally at 15, and which as may be seen in Fig. 1, is disposed substantially centrally of the tub in spaced apart relation to the bottom and wall thereof, to permit free circulation of the washing fluid and clothes, around and beneath said impeller member.

The driving mechanism for vertically reciprocating the impeller member includes an electric motor 16, provided with a driving pulley 17, which through the medium of a belt 18, drives a pulley 19. It is to be understood that the pulley 19 is connected in a conventional manner to a worm gear speed reducer mechanism of conventional design, enclosed within the housing 20. The worm gear (not shown) may be understood to be mounted on a horizontal shaft, and rigidly connected to the outer portion of said shaft is a crank arm 22, the outer end of which is pivotally connected by a pin 23 to the lower end of an upwardly extending pitman 24. The upper end of said pitman is

5 journaled on a pin 26 carried in a block 27, journaled on and surrounding an impeller shaft 29. Said block 27 is confined between a pair of collars 30, fixedly secured to the impeller shaft by pins 31. The lower end of the impeller shaft is formed with a plurality of helical splines 33, having cooperative engagement with internal splines 34 formed in the lower portion of an upwardly extending tubular standard 36, the lower 10 end of which is formed with a foot 37, secured to the frame 14. As will hereinafter appear, the splines 33 and 34 impart rotary motion to the impeller shaft 29, when the latter is vertically reciprocated by the medium of the drive mechanism, above described.

15 The upper portion of the impeller shaft 29 projects centrally through the bottom of the tub 10 a substantial distance, and supports the impeller member 15. Surrounding the upper portion of the impeller shaft 29, which protrudes into the tub, is an upstanding tubular standard 40, the lower end of which is provided with a flange 41, forming a transverse shoulder, adapted to be seated tightly against the bottom of the 20 tube surrounding the opening 10a, with a gasket 42 interposed between said flange and the bottom of the tub. Said flange portion 41 includes a depending externally threaded portion 44 projecting downwardly through the opening 10a, below the bottom of the tub, and has threaded connection with a block 45, the upper end of which forms a transverse shoulder for tightly seating against the under surface of the bottom of the tub, surrounding the aperture 10a with a 25 gasket 46, interposed therebetween. The bottom of the block 45 is formed with depending ears 47, which are rigidly connected to a brace or cross member 48, the ends of which are rigidly attached to the inner wall of the skirt 11. It 30 will now be apparent that when the lower end of the tubular standard 40 is tightly threaded into the block 45 with the gasket members 42 and 46 interposed therebetween, a fluid-tight seal is formed around the opening 10a in the 35 bottom of the tub.

40 It is to be understood that the tubular standard 40 projects upwardly into the interior of the hollow cavity of the impeller member 15 a substantial distance, preferably above the level of the 45 water in the tub, so as to avoid the necessity of a water seal. The upper end of the impeller shaft 29 is provided with a suitable head or block 50, preferably of polygonal form, for cooperative engagement in a socket 15b, formed in the upper end of the interior of the impeller member 15, and said impeller member is rigidly attached or connected to the block 50 in any suitable manner, and as herein shown, by means of a set screw 15c.

50 The impeller member, designated at 15, preferably is formed as a hollow casting and includes a main body portion 55 of substantially circular outline, disposed transversely of the impeller shaft 29. The upper portion of the impeller 55 member is formed with a head 56 of slightly convex contour, which is joined to the main body portion 55 by a tubular concave wall 57. The purpose of the head 56, in addition to causing action of the water by the vertical reciprocatory movement thereof, also tends to reduce the amount of splash of the washing fluid while the impeller member is in motion.

55 The impeller member is provided with a multiplicity of upwardly extending vanes 58, herein shown as four in number, circumferentially

spaced apart substantially equal distances. As may be seen in the drawings, corresponding faces indicated at 59, of these respective vanes are disposed approximately in radial planes, while the opposite faces, designated at 60 are inclined or sloped in planes at an angle to radial.

60 It will now be apparent that when the impeller shaft 29 is imparted simultaneous vertically reciprocatory motion and horizontal oscillating motion about its axis, the impeller member, which is rigidly attached to the impeller shaft, will in one direction of rotation and vertical movement act on the washing fluid and clothes to impart thereto an outward direction of movement, at an angle oblique to radial, causing circulatory movement of the entire body of fluid and clothes immersed therein around the impeller member. This motion of the washing fluid and clothes is modified to a large extent by the vertical movement of the impeller member, which also imparts motion to the body of the washing fluid and clothes in a vertical direction, the combined or modified action resulting in substantial turbulence and swirling of the washing fluid and clothes therein, for effecting frequent flexings and turning over of the clothes for performing an efficient cleansing operation thereupon. Due to the contour of the faces 60 of the vanes of the impeller member, it will be apparent that on the downstroke of the impeller member, the motion of the washing fluid and clothes in a vertical plane substantially approximates a radial direction, while at the same time the vertical movement of the impeller member imparts motion to the body of the washing fluid in a vertical 35 direction. It will now be manifest that by continuous reciprocatory, and oscillatory action of the impeller member, the body of clothes will be gradually and continuously advanced in one circulatory direction around the impeller member, 40 in a direction which corresponds to the direction of movement imparted thereto by the action of the faces 59 of the impeller vanes 58.

45 Although the action on the washing fluid and clothes, by virtue of the construction above described, is relatively vigorous, yet it is gentle on the clothes, in that it does not impose severe strains or abrading action on the fabric and results in promptly effecting a thorough cleansing operation upon the clothes.

50 It is to be understood that the term "clothes" as used herein and in the claims, is to be accorded the general meaning in the art, namely, as including any washable fabric or sheet material in addition to wearing apparel.

55 Although I have herein shown and described a preferred embodiment of my invention, manifestly it is capable of modification and rearrangement of parts without departing from the spirit and scope thereof. I do not, therefore, wish to be understood as limiting this invention to the precise embodiment herein disclosed, except as it may be so limited by the appended claims.

I claim:

1. In a washing machine, the combination with 65 a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes 70 75

around and beneath said impeller, said impeller member comprising a body portion of substantial area extending transversely of the axis of the tub, and a set of circumferentially spaced apart vertically disposed vanes extending upwardly from said body portion, corresponding faces of said set of vanes being formed and positioned for imparting circulatory motion to the body of washing fluid and clothes, around said impeller member, during oscillation of the impeller member in one direction, the opposite faces of said vanes extending at an angle oblique to radial to impart approximately radial motion to the body of washing fluid and clothes, during reverse oscillation of the impeller member.

2. In a washing machine, the combination with a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes around and beneath said impeller, said impeller member comprising a bottom portion of substantial area extending transversely of the axis of the tub, a head disposed in spaced relation to the bottom portion, the portion intermediate the bottom portion and the head being of less cross-sectional area than said head, and a set of circumferentially spaced apart vertically disposed vanes connecting said bottom portion, intermediate portion and head.

3. In a washing machine, the combination with a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes around and beneath said impeller, said impeller member comprising a body portion of substantial area extending transversely of the axis of the tub, a head disposed in spaced relation to the body portion, and a set of circumferentially spaced apart vertically disposed vanes connecting said body portion and head, corresponding faces of said set of vanes being formed and positioned for imparting circulatory motion to the body of washing fluid and clothes, around said impeller member, during oscillation of the impeller member in one direction, the opposite faces of said vanes extending at an angle oblique to radial and sloping downwardly and outwardly to impart approximately radial motion to the washing fluid and clothes, during the combined reverse oscillation and upstroke of the vertical reciprocation of the impeller member.

4. In a washing machine, the combination with a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes

around and beneath said impeller, said impeller member comprising a body portion of substantial area extending transversely of the axis of the tub, a head disposed in spaced relation to the body portion, and a set of circumferentially spaced apart vertically disposed vanes connecting said body portion and head, corresponding faces of said set of vanes being formed and positioned for imparting circulatory motion to the body of washing fluid and clothes, around said impeller member, during oscillation of the impeller member in one direction, the opposite faces of said vanes sloping downwardly and outwardly to impart approximately radial motion to the washing fluid and clothes, during the upstroke of the vertical reciprocation of the impeller member.

5. In a washing machine, the combination with a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes around and beneath said impeller, said impeller member comprising a body portion of substantial area extending transversely of the axis of the tub, and a set of circumferentially spaced apart vertically disposed vanes extending upwardly from said body portion, corresponding faces of said set of vanes being formed and positioned for imparting circulatory motion to the body of washing fluid and clothes, around said impeller member, during oscillation of the impeller member in one direction, the opposite faces of said vanes extending at an angle oblique to radial and sloping downwardly and outwardly to impart approximately radial motion to the washing fluid and clothes, during the combined reverse oscillation and upstroke of the vertical reciprocation of the impeller member.

6. In a washing machine, the combination with a tub adapted to contain washing fluid and clothes to be washed, of an impeller shaft having a portion extending upwardly through the bottom of the tub, means for simultaneously imparting vertically reciprocating and horizontally oscillating motion to said impeller shaft, and an impeller member mounted on the upper end of said shaft, within the tub, and disposed in spaced relation to the bottom and wall thereof to permit free circulation of the washing fluid and clothes around and beneath said impeller, said impeller member comprising a body portion of substantial area extending transversely of the axis of the tub, a head disposed in spaced relation to the body portion, and a set of circumferentially spaced apart vertically disposed vanes connecting said body portion and head, corresponding faces of said set of vanes being formed and positioned for imparting circulatory motion to the body of washing fluid and clothes, around said impeller member, during oscillation of the impeller member in one direction, the opposite faces of said vanes extending at an angle oblique to radial and sloping downwardly and outwardly to impart approximately radial motion to the washing fluid and clothes, during the combined reverse oscillation and upstroke of the vertical reciprocation of the impeller member.

ANTHONY W. MOLINARE.
